UNITED STATES PATENT OFFICE.

GEORGE W. PIGGOTT, OF NEW YORK, N. Y., ASSIGNOR TO HARTFORD CARPET COMPANY, OF HARTFORD, CONNECTICUT.

DESIGN FOR CARPET.

Specification forming part of Design No. **11,304**, dated July 22, 1879; application filed June 12, 1879.
[Term of patent 3½ years.]

To all whom it may concern:

Be it known that I, GEORGE W. PIGGOTT, of the city of New York, county and State of New York, have invented a new and original Design for a Carpet, of which the following is a specification.

The accompanying photographic illustration represents a face view of my newly-designed carpet.

This invention relates to a new and original design for a carpet, oil-cloth, or similar fabric.

It consists of the new ornamentation and grouping of the figures constituting the design, as hereinafter more fully pointed out.

In the photographic illustration, the letter *a* represents a rectangular irregular figure, and *b c* are two L-shaped figures, situated at one side of *a*.

d e are two rectangular parallelograms, placed at the side of the figures *b c*. Beneath the figure *a* are two L-shaped figures, *f g*, the latter figure having a rectangular projection, as shown.

Beneath the figures *c* and *e* are, first, a figure, *h*, composed of two parallelograms, and, secondly, an L-shaped figure, *i*.

Beneath the figures *g*, *h*, and *i* are respectively placed three rectangular parallelograms, *j*, *k*, and *l*, and L-shaped figure *m*, having an oblique corner, being situated between the figures *h*, *i*, and *l*.

Upon the carpet are, furthermore, represented two rectangles, *n* and *o*, and the L-shaped figure *p*.

All the above-described figures are arranged as shown in the photographic illustration to

form one harmonious design. They are ornamented as follows: The figures *a*, *b*, *d*, and *e* contain floral embellishment. *c* is partly surrounded by border. The figure *f* is made in sections, having differently-colored backgrounds, and contains flowers and small geometrical patterns. *g* is richly ornamented, and is partly surrounded by border, as are also the figures *h*, *i*, *j*, and *m*. *k*, *l*, *o*, and *p* contain floral groups. The figure *n* has a broad stripe at one side, as shown.

I claim as my invention—

1. The design for a carpet, consisting of the figures *a*, *b*, and *c*, substantially as shown.
2. The design for a carpet, consisting of the figures *b*, *c*, *d*, and *e*, substantially as shown.
3. The design for a carpet, consisting of the figures *f* and *g*, substantially as shown.
4. The design for a carpet, consisting of the figures *c*, *h*, and *i*, substantially as shown.
5. The design for a carpet, consisting of the figures *h i l m*, substantially as shown.
6. The design for a carpet, consisting of the figures *j h m k*, substantially as shown.
7. The design for a carpet, consisting of the figures *p m l n*, substantially as shown.
8. The design for a carpet, consisting of the figures *p d n o*, substantially as shown.
9. The design for a carpet, consisting of the figures *a b c d e f g h i j k l m n o p*, substantially as shown.
